[57] CLAIM

The ornamental design for a weapon sight, as shown and described.

DESCRIPTION

FIG. 1 is a front perspective view of a weapon sight, showing my new design;

FIG. 2 is an elevation view of the right side thereof;

FIG. 3 is a bottom plan view thereof; and

FIG. 4 is an end view thereof when FIG. 1 is viewed from the weapon sight end at the right therein.

FIG. 2

FIG. 3
